US0D1028975S

(12) **United States Design Patent** (10) Patent No.: **US D1,028,975 S**
(45) Date of Patent: ** May 28, 2024

(54) **SMART WATCH**

(71) Applicant: **An Yang**, Shenzhen (CN)

(72) Inventor: **An Yang**, Shenzhen (CN)

(**) Term: **15 Years**

(21) Appl. No.: **29/778,323**

(22) Filed: **Apr. 13, 2021**

(51) LOC (14) Cl. **14-02**

(52) U.S. Cl.

USPC **D14/344**

(58) **Field of Classification Search**

USPC .... D14/344, 138 R; D10/30, 31, 32, 38, 70; D11/3; D24/167

(57) **CLAIM**

The ornamental design for a smart watch, as shown and described.

DESCRIPTION

FIG. 1 is a perspective view of the smart watch showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict portions of the smart watch that form no part of the claimed design.

1 Claim, 7 Drawing Sheets
